UNITED STATES PATENT OFFICE.

JAMES A. HENRY AND THADDEUS S. WAIT, OF STURGIS, MICHIGAN.

FORMING MACHINE.

Application filed January 9, 1922. Serial No. 528,107.

To all whom it may concern:

Be it known that we, JAMES A. HENRY and THADDEUS S. WAIT, citizens of the United States, residing at Sturgis, county 5 of St. Joseph, State of Michigan, have invented certain new and useful Improvements in Forming Machines, of which the following is a specification.

This invention relates to improvements in 10 forming machines.

We have especially designed our improvements for the forming of curtain rods and in the accompanying drawing we have illustrated the same as adapted for that purpose. Our improvements are, however, readily adapted to the forming of other and heavier channel-shaped articles.

The main objects of the invention are:

First, to provide an improved machine 20 for the forming of curtain rods which is of large capacity and at the same time produces a superior product in that it is very uniform.

Second, to provide an improved machine 25 of the class described which may be adjusted to compensate for variations in the gage of the metal worked upon.

Further objects, and objects relating to 30 structural details, will definitely appear from the detailed description to follow.

We accomplish the objects of our invention by the devices and means described in the following specification. The invention is clearly defined and pointed out in the 35 claims.

A structure which is a preferred embodiment of our invention is clearly illustrated in the accompanying drawing, forming a part of this application, in which:

Fig. I is a plan view of a bending machine embodying the features of our invention, as adapted for the forming of curtain rods.

Fig. II is a side elevation, parts being broken away to show structural details and other parts being shown conventionally.

Fig. III is a side elevation of the side opposite from that shown in Fig. II.

Fig. III^A is a detail horizontal section on a line corresponding to line 3^A—3^A of Fig. III, showing the arrangement of the work supports relative to the forming rollers.

Fig. III^B is a detail section on a line corresponding to line 3^B—3^B of Figs. III and III^A.

Fig. IV is a transverse section through the feed rolls on a line corresponding to line 4—4 of Figs. I, II and III, the shafts being shown in full lines for convenience in illustration.

Fig. V is a detail section on a line corresponding to line 5—5 of Fig. I, showing details of the first set of forming rollers.

Fig. VI is a detail section on a line corresponding to line 6—6 of Fig. I, showing details of the second set of forming rollers.

Fig. VII is a detail section on a line corresponding to line 7—7 of Fig. I, showing details of the third set of forming rollers.

Fig. VIII is a detail section on a line corresponding to line 8—8 of Fig. I, showing details of the fourth set of forming rollers.

Fig. IX is a detail section on a line corresponding to line 9—9 of Fig. I, showing details of the fifth set of forming rollers.

Fig. X is a perspective view of a piece of the finished work.

In the drawing similar reference characters refer to similar parts throughout the several views, and the sectional views are taken looking in the direction of the little arrows at the ends of the section lines.

Referring to the drawing, the base 1 is in the form of a bar extending the length of the machine and provided with shoulders 2 against which the supporting plates 3 are bolted. These are secured to the base by the bolts or screws, indicated at 4. These plates have bearing openings 5 for the lower series of shafts 6 and openings 7 for the bearing members 8 of the upper series of shafts 9. The shafts 6 and 9 are arranged in pairs, the bearing members 8 having eccentric portions 10 engaging the bearing openings 7 so that by rotating these bearing members 8 the shafts 9 are adjusted towards and from the shafts 6.

To secure the bearing members 8 in their adjusted positions one of the supporting plates has inverted T-shaped slots 11 disposed between adjacent pairs of bearing openings with their cross or horizontal portions 12 opening into the bearing openings as

shown in Fig. II. Screws 13 extend through these slots so that the partially severed portions of the plates may be clamped upon the bearing members, thus retaining them in their adjusted positions. At the ends of the plates are slots 14 extending to the bearing openings.

The shafts are connected in pairs by the gears 15 and these pairs of gears are connected by the pinions 16, the center pinion 17 being driven from the shaft 18. With this arrangement all of the shafts are driven and at uniform speeds.

The feeding and forming rolls are mounted on the pairs of shafts. The rolls 19 and 20 constitute the feed rolls. The roll 19 is provided with peripheral flanges 21 adapted to receive the work, as 22, while the roll 20 is of such size as to fit between the flanges,— see Fig. IV. The work is thus aligned and fed to the first pair of forming rollers. This first pair of forming rolls 23 and 24 is adapted to initially channel the work, as shown in Fig. V, the roll 24 having a channeled periphery, the ends of which are disposed at an obtuse angle to the bottom. The roll 24 has a correspondingly entrant shaped periphery which rolls the work into the channel of the roll 23.

The second pair of forming rolls 25 and 26,— see Fig. VI, is substantially the same as the first except that the angle is more acute, thus further forming the work.

The third pair of rolls 27 and 28 is shaped to receive the flanges of the work at right angles, the channel of the roll 27 having its sides at right angles to the axis of the roll, the entrant periphery of the coacting roll being correspondingly shaped.

The fourth pair of rolls 29 and 30 is adapted to turn the edges of the work inwardly, the roll 29 having an A-shaped periphery with a channel therein having rounded corners. The roller 30 has a V-shaped periphery which engages the projecting edges of the work, turning them inwardly, as shown in Fig. VIII.

The fifth pair of forming rolls 31 and 32 is adapted to further turn the edges of the work inwardly. The roll 31 has a channeled periphery with curved sides and is of such depth that the edges of the work project well above the periphery thereof. The roller 32 has a stepped periphery providing a peripheral rib 33 which is adapted to engage the work between its flanges, holding it against the bottom of the channel of the roller 31, and shoulders 34 which engage the edges of the work turning them inwardly, as shown in Fig. IX.

The sets of rollers 35 and 36 and 37 are shaped to correspond to the rollers 31 and 32 and serve to support the work as it passes from the set of rollers 31 and 32 and also

to engage the flanges so that they do not spring or open up.

Between the sets of rollers we provide work supports 38 supported by the blocks 39 so that the supports are in substantially the plane of the peripheries of the bottom rolls. This prevents the work bulging between the rollers and guides the work from one pair to the other.

Our improved machine is of large capacity and the work produced is very uniform. The structure requires little attention in use and may be fed or operated by an unskilled workman.

We have illustrated and described our improvements as we have embodied or adapted the same for the forming of curtain rods.

We have not attempted to illustrate or describe other modifications or adaptations as we believe the disclosure made will enable those skilled in the art to which our invention relates to embody or adapt the same as may be desired.

Having thus described our invention, what we claim as new and desire to secure by Letters Patent, is:

1. In a structure of the class described, the combination of feed and forming rollers arranged in coacting pairs one above the other, shafts therefor, connecting gears for each pair of shafts, connecting gears for the several pairs of gears, spaced supporting plates for said shafts having bearing member openings for the upper shafts, one of said plates having inverted T-shaped slots disposed between and with the cross portions of the slots opening into adjacent bearing member openings, bearing members for said upper shafts having eccentric portions disposed in said bearing member openings whereby the shafts may be adjusted to adjust the rollers, and screws engaging the slotted portions of said plate to clamp the same upon the said bearing members whereby they are secured in their adjusted positions.

2. In a structure of the class described, the combination of feed and forming rollers arranged in coacting pairs one above the other, spaced supporting plates for said shafts having bearing member openings for the upper shafts, one of said plates having inverted T-shaped slots disposed between and with the cross portions of the slots opening into adjacent bearing member openings, bearing members for said upper shafts having eccentric portions disposed in said bearing member openings whereby the shafts may be adjusted to adjust the rollers, and screws engaging the slotted portions of the plate to clamp the same upon the said bearing members whereby they are secured in their adjusted positions.

3. In a structure of the class described, the combination of a pair of feed rollers,

the bottom roller having peripheral guide flanges disposed at right angles to the axis thereof, the coacting top feed roller being adapted to engage the work between said flanges, a series of sets of forming rollers, one roller of each set having a channeled periphery and the other a correspondingly shaped entrant periphery, the angles of the sides of the succeeding rollers increasing to a right angle, a set of forming rollers succeeding the last set of such series, one of which has an A-shaped periphery with a channel at the apex thereof, the coacting roller having a V-shaped channeled periphery embracing the periphery of the coacting roller to turn the edges of the work projecting from the channel thereof inwardly, a set of forming rollers arranged to receive the work from the last described set, one of which is provided with a channeled periphery from which the inturned edges of the work project, and the coacting roller having a stepped periphery providing a central annular portion engaging the work at the bottom of the channel and shoulders at each side engaging the edges of the work with the edges in the angles of said shoulders, and work supports arranged between adjacent rollers to support the work substantially in alignment with the peripheries of the bottom rollers.

4. In a structure of the class described, the combination of a pair of feed rollers, the bottom roller having peripheral guide flanges disposed at right angles to the axis thereof, the coacting top feed roller being adapted to engage the work between said flanges, a series of sets of forming rollers, one roller of each set having a channeled periphery and the other a correspondingly shaped entrant periphery, the angles of the sides of the succeeding rollers increasing to a right angle, a set of forming rollers succeeding the last set of such series, one of which has an A-shaped periphery with a channel at the apex thereof, the coacting roller having a V-shaped channeled periphery embracing the periphery of the coacting roller to turn the edges of the work projecting from the channel thereof inwardly, and a set of forming rollers arranged to receive the work from the last described set, one of which is provided with a channeled periphery from which the inturned edges of the work project, and the coacting roller having a stepped periphery providing a central annular portion engaging the work at the bottom of the channel and shoulders at each side engaging the edges of the work with the edges in the angles of said shoulders.

5. A structure of the class described comprising a set of forming rollers, one of which has an A-shaped periphery with a channel

at the apex thereof, the corners of the channel being curved, the coacting roller having a V-shaped channeled periphery embracing the periphery of the coacting roller to turn the edges of the work projecting from the channel thereof inwardly, and a set of forming rollers arranged to receive the work from the last described set, one of which is provided with a channeled periphery from which the inturned edges of the work project, and the coacting roller having a stepped periphery providing a central annular portion engaging the work at the bottom of the channel and shoulders at each side engaging the edges thereof turning them inward with the edges in the angles of said shoulders.

6. A structure of the class described comprising a set of forming rollers, one of which has an A-shaped periphery with a channel at the apex thereof, the coacting roller having a V-shaped channeled periphery embracing the periphery of the coacting roller to turn the edges of the work projecting from the channel thereof inwardly, and a set of forming rollers arranged to receive the work from the last described set, one of which is provided with a channeled periphery from which the inturned edges of the work project, and the coacting roller having a stepped periphery providing a central annular portion engaging the work at the bottom of the channel and shoulders at each side engaging the edges thereof turning them inward, with the edges in the angles of said shoulders. 85 90 95

7. A structure of the class described comprising a set of forming rollers, one of which has an A-shaped periphery with a channel at the apex thereof, the coacting roller having a V-shaped channeled periphery embracing the periphery of the coacting roller to turn the edges of the work projecting from the channel thereof inwardly, and a set of forming rollers arranged to receive the work from the last described set, one of which is provided with a channeled periphery from which the inturned edges of the work project, and the coacting roller having a stepped periphery providing a central annular portion engaging the work at the bottom of the channel and shoulders at each side engaging the edges thereof and turning them inward. 100 105 110 115

8. In a structure of the class described, the combination of a pair of feed rollers, the bottom roller having peripheral guide flanges disposed at right angles to the axis 120 thereof, the coacting top feed roller being adapted to engage the work between said flanges, a plurality of sets of forming rollers, one roller of each set having a channeled periphery and the other a correspondingly shaped entrant periphery, the angles of the sides of the succeeding rollers increasing to a right angle, and a set of forming rollers 125

succeeding the last set of such series and one of which has an A-shaped periphery with a channel at the apex thereof, the corners of the channel being curved, the coacting roller having a V-shaped channeled periphery embracing the periphery of the coacting roller to turn the edges of the work

projecting from the channel thereof inwardly.

In witness whereof, we have hereunto set 10
our hands and seals.
